UNITED STATES PATENT OFFICE.

JAMES EDWARDS TATE, OF CINCINNATI, OHIO.

DESIGN FOR A KITCHEN-CABINET.

SPECIFICATION forming part of Design No. 31,983, dated December 12, 1899.

Application filed November 6, 1899. Serial No. 736,054. Term of patent 7 years.

To all whom it may concern:

Be it known that I, JAMES EDWARDS TATE, a citizen of the United States, residing at Cincinnati, in the county of Hamilton and State of Ohio, have invented a Design for a Kitchen-Cabinet; and I do declare the following to be a full, clear, and exact description of the invention, such as will enable others skilled in the art to which it appertains to make and use the same.

My invention relates to a design for a kitchen-cabinet, and the figure in the drawing is a perspective view of the kitchen-cabinet, illustrating the design which is the subject of my invention.

The essential feature of my design is a rectangular cabinet having a forwardly-project-

ing base, closed back and sides, and an open front, as illustrated in the figure, which is sufficiently clear of comprehension to those familiar to the art.

Having thus fully described my invention, what I claim as new and useful, and desire to secure by Letters Patent of the United States, is—

The design for a kitchen-cabinet, substantially as herein shown and described.

In testimony whereof I have hereunto set my hand in presence of two subscribing witnesses.

JAMES EDWARDS TATE.

Witnesses:

F. L. MAYES,
ED. WHEELER.
